United States Patent

Des. 240,756
Patented July 27, 1976

240,756

DIGGER TOOTH

Dwight M. Phillips, Corona Del Mar, Calif., assignor to
Corona Forge Company, Corona, Calif.

Filed June 11, 1975, Ser. No. 586,043

Term of patent 14 years

Int. Cl. D15—04

U.S. Cl. D39—1 R

FIG. 1 is a view of one of two similar sides of the design of a digger tooth;

FIG. 2 is a top view of the design;

FIG. 3 is a bottom plan view of the design;

FIG. 4 is a front view of the design; and

FIG. 5 is a rear view of the design.

I claim:

The ornamental design for a digger tooth, as shown.
